[57] CLAIM

The ornamental design for a food dispenser, as shown and described.

DESCRIPTION

FIG. 1 is a perspective view of the food dispenser embodying my new design, looking angularly at the front thereof;

FIG. 2 is a front elevational view;

FIG. 3 is a rear elevational view;

FIG. 4 is a side elevational view;

FIG. 5 is a top view looking down on the food dispenser.

FIG. 2.

FIG. 3.
